(57) **CLAIM**

We claim the ornamental design for a display screen with graphical user interface, as shown and described.

DESCRIPTION

The sole FIGURE is a front view of a display screen with graphical user interface showing the new design.

The evenly spaced broken lines illustrate portions of the graphical user interface and environment that form no part of the claimed design. The evenly spaced broken line under the broken words “Process Definition” overlaps a solid line but forms no part of the claimed design. The dash-dot lines illustrate the boundary of the display screen and form no part of the claimed design.
